UNITED STATES PATENT OFFICE.

ALLEN T. DEXTER, OF CLEVELAND, OHIO, ASSIGNOR TO THE NATIONAL MALLEABLE CASTINGS COMPANY, OF CLEVELAND, OHIO.

CAST-STEEL CHAIN.

1,365,770.

Specification of Letters Patent. Patented Jan. 18, 1921.

Application filed June 7, 1919. Serial No. 302,567.

To all whom it may concern:

Be it known that I, ALLEN T. DEXTER, a citizen of the United States, residing at Cleveland, Cuyahoga county, Ohio, have invented new and useful Improvements in the Manufacture of Cast-Steel Chain, of which the following is a specification, reference being had to the accompanying drawings, in which—

10 Figure 1 is a vertical longitudinal section of two tiers of mold sections employed in carrying out my invention; Fig. 2 is a top plan view thereof; Fig. 3 is a perspective of a mold section; and Fig. 4 is an end elevation of mold sections showing a modified form of pouring cup which may be employed in carrying out my invention.

My invention relates to the making of cast steel chain links in the form of a continuous chain. In carrying out my invention I prefer to employ sand mold sections arranged in tiers so as to form impressions for complete sections or shots of chain in order that two or more such shots or sections may be formed at one series of pours. My invention also consists in the various steps and features which I shall hereinafter describe and claim.

Referring to the drawings, in which I have shown mold sections suitable for carrying out my invention, the mold sections are preferably formed in a mold box such as I have described and claimed in my co-pending application filed of even date herewith Serial No. 302,568 for the manufacture of cast steel chain. Each mold section contains on one face of the mold an incomplete half impression A and within the body of the mold two separate quarter link impressions B, which extend within the impression A and intersect the plane thereof. Each mold section (except when used as a bottom section) also has impressions C for gates or shrinkheads which lead into the quarter link impressions B. When it is desired to form a section of chain links a series of quarter molds 2 (made without gate impressions) are arranged end to end, as is shown in Fig. 1, with the projections 6 on the end of one section fitting in corresponding recesses 7 in the end of the next adjacent section, and preformed links are placed in the impressions A. A series of complementary quarter molds 3 are next put in place with 55 their impressions A turned downwardly

facing the impressions A in the bottom or first mentioned series, with the impressions B of the two series in registry and with the complementary gate impressions C in the second mentioned series facing each other, thus completing a tier of mold sections. A third series of quarter molds 4 is then placed on top of the first tier, but with the impressions for the preformed links uppermost and the gate impressions in registry with those of the second series. A second set of preformed links is then placed in the impressions A and then a fourth series of quarter molds 5 with the impressions A facing the impressions A of the third series is placed in position, so arranged that the various complementary quarter link and gate impressions are in registry, thus completing the second tier of mold sections.

Upon the pouring gates in the upper tier 75 of molds pouring cups 8 are placed. The stack of molds is then weighted to prevent the lifting of the molds by the metal during the pouring operation. The meeting edges of the quarter molds are luted with a siliceous material where this is deemed necessary, and the stack is ready for pouring. It will be seen that the impressions B for the links to be poured are arranged on edge and that in pouring the metal will be supplied to 85 and through the central section of each link.

The molds are then poured, the metal passing through pouring cups 8, the gates C, through the stud impression b of the upper link impression B, through the lower 90 gate C, and then into the impression B for the lower link. As the pouring is continued the metal rises and fills the upper impressions B and the cups 8. The molds are then broken up and two shots or connected sections of chain are found to have been formed. It is obvious that as many links as are desired may be connected together by the method and molds which I have described.

If desired, four sections of chain may be cast at one time, as is shown in Fig. 4, by pouring two rows of mold sections through a series of pouring cups 9, arranged so that two connecting links in each row may be 105 poured at the same time.

It has been found to be of great advantage to cast the connecting links on edge and with the links arranged one above the other, since it greatly facilitates the casting 110

operations and the production of sound links.

I have also effected a considerable economy of space and sand, by making the mold sections narrower than the precast links, as it is not necessary that these precast links be contained wholly within the mold sections, since the impressions therefor are not poured.

10 The terms and expressions which I have employed are intended to be used as terms of description and not of limitation since I recognize that modifications of the steps and features which I have described may be 15 made within the scope of the invention claimed.

What I claim is:

1. The herein described process of making cast steel chain, which comprises arranging 20 a series of mold sections each containing quarter link impressions therein, superimposing upon the first series of mold sections a second series containing impressions complementary to those of the first series, and 25 also containing gate impressions, thereby forming a set of complete molds, placing other similarly arranged series of mold sections upon said first set of molds and with connecting impressions to form a second set 30 of completed molds, and simultaneously forming complete chain links in two separate chains by a single pour of metal.

2. The herein described process of making cast steel chain which comprises arranging 35 a series of mold sections each containing within it separate quarter link impressions and also having a part impression for another link, assembling such mold sections to form a complete link impression 40 from the quarter link impressions with the

quarter link impressions arranged in a vertical plane and with preformed links in the part impressions, and extending beyond the sides of the mold, and pouring the link through the top edge of the impression, 45 thereby forming a plurality of interconnected links.

3. A mold stack for casting chain, which comprises a plurality of superimposed tiers of mold sections, each tier containing link 50 impressions interlinked in a chain of impressions, gates connecting impressions of one tier with the impressions of another tier, and a pouring gate leading into each such connected pair of link impressions, where- 55 by chain links in two separate chains are formed by a single pour of metal.

4. A mold stack for casting chain, which comprises a plurality of superimposed tiers of mold sections, each tier containing complete link impressions alternating with impressions for preformed links, gates connecting the complete impressions of one tier with the impressions of another tier, and a pouring gate connected with each link impression in the upper tier, whereby chain links in two separate chains are formed by a single pour of metal.

5. A mold stack for casting chain, which comprises a plurality of mold sections arranged in sets, each set containing a plurality of complete link impressions arranged one above the other, a feeder connecting such link impressions, and a pouring gate connected with one of said link impressions, 75 to permit the metal to flow successively into the said link impression to form separate chain links.

ALLEN T. DEXTER.
